ABSTRACT

A marble game is described in which a playing surface is provided having designations for the locations of two marbles in contact with each other and with designations of a plurality of shooting positions for a third marble, these being points awarded a player for a shot from each shooting position that dislodges one of the two marbles without dislodging or moving the other. Alternatively, the marbles can be replaced by disk objects, such as dimes or pennies.

FIG. 1B

FIG. 1C

FIG. 1D

FIG. 2A

FIG. 2B

FIG. 2C

MARBLE/DISK GAME

BACKGROUND OF THE INVENTION

In years gone by, there was great enthusiasm for a marble game in which the object was to knock marbles initially positioned in the center of an eight-foot ring outside of the ring by shooting a marble held between the thumb and fingers with an outward snap of the thumb. For such a game to be feasible an absolutely level ring, usually formed with clay soil was provided by public parks and business enterprises. Unfortunately such rings are no longer available.

SUMMARY OF THE INVENTION

In accordance with one embodiment of this invention, a game is provided in which the marble shooting accuracies of players can be respectively compared without requiring a large clay ring. Two marbles are placed in contact with each other on a level playing surface, and the players shoot a shooter marble from designated shooting positions on the surface so as to move one of them without moving the other. For a successful shot from each position a player earns a number of points related to the difficulty involved. After a preselected number of shots, the winner is the player with the most points. Alternatively, in another embodiment of the invention, the marbles can be replaced with disk objects, such as dimes, or pennies. Also, the playing surface can be made portable.

BRIEF DESCRIPTION OF THE DRAWINGS

FIG. 1A is a top view of a playing surface on which two marbles or disk objects are shown in playing position;

FIG. 1B is a section BB of FIG. 1A when the playing surface is hard;

FIG. 1C illustrates a section BB of FIG. 1B if the playing surface is soft;

FIG. 1D is a marble or disk used as a shooter;

FIG. 2A illustrates the appearance of a playing surface in which shooting lines are replaced by shooting positions;

FIG. 2B illustrates the appearance of a playing surface in which aiming lines are shown for each shooting position; and

FIG. 2C illustrates the appearance of a playing surface in which aiming sectors are shown for each shooting position.

DETAILED DESCRIPTION OF THE INVENTION

In FIG. 1A, a smooth flat playing surface 2 is shown having marbles M₁ and M₂, preferably of identical weight and size, mounted thereon in contact with each other. As shown in the FIGS. 1B and 1C, the marbles M₁ and M₂ are respectively mounted in depressions D₁ and D₂ formed in the playing surface 2. If the playing surface 2 is made of hard material such as plastic, the depressions D₁ and D₂ are preformed therein as shown in FIG. 1B, but if the playing surface 2 is made of soft material such as felt, the depressions D₁ and D₂ may be formed by the weight of the respective marbles M₁ and M₂ as shown in FIG. 1C. Whereas depressions D₁ and D₂ of some sort are preferable in order to prevent the marbles M₁ and M₂ from moving in response to forces other than those resulting from the impact of a shooter marble, they are not necessary. If the depressions D₁ and D₂ are not preformed, the locations for the marbles M₁ and M₂ are designated by dots d₁ and d₂, but both depressions D₁ and D₂ and dots d₁ and d₂ may be used.

FIG. 1D shows a shooter marble M₃ that may or may not be the same weight and/or size as the marbles M₁ and M₂. As described in greater detail below, an object of the game is for a player to fire the shooter marble M₃ at either M₁ or M₂ in a manner to move either M₁ or M₂ without moving both.

Note that for purposes of description, the present game invention is described using marbles for one embodiment. In another embodiment, disk objects, such as dimes or pennies can be used in place of the marbles. If disk objects are used, no depressions are included on the associated playing surfaces, and D₁ and D₂ would be printed positions for placement of the disks on the playing surface.

Lines L₁ through L₅ that are parallel to a line joining the dots d₁ and d₂ and/or the depressions D₁ and D₂ are located at different respective distances from that line. Points to be earned by shooting a marble from shooting positions at any point along a line are indicated at ends of the lines. The points earned are approximately commensurate with the distance involved. By way of example, the points earned by shooting from shooting positions along the lines L₁ through L₅ may be respectively 5, 7, 10, 14, and 20 as indicated. Because of the geometry involved, it is easier to make a successful shot from the ends of the lines L₁ through L₅ than from any point along them.

Preferably, lines L₆ and L₇ that are perpendicular to a line joining dots d₁ and d₂ and/or the depressions D₁ and D₂ and which respectively pass through d₁ and d₂, and/or D₁ and D₂ are formed on the playing surface 2. As shown, a player making a successful shot from a shooting position at their end that is remote from the marbles M₁ and M₂ will earn a maximum number of points such as 75. Although this is very difficult, it gives a player with a low score a chance to win and thus maintain interest in the game.

Because the size of the marbles M₁ and M₂ in the drawings relative to the spacing of the lines L₁ through L₇ may make it appear that it would be difficult to locate the shooting positions from which a shot is made with great accuracy, the actual dimensions of the playing surface 2 are such that this is not the case. For example, the lines L₁ through L₅ may be six inches apart, and the lines L₆ and L₇ would be one-half inch apart if the marbles M₁ and M₂ are one-half inch in diameter. The distance between L₁ and a line passing through d₁ and d₂ and/or D₁ and D₂ could be eighteen inches. The widths of the playing surface 2 could be from twelve inches to twenty-four inches.

In playing a game, each player would be given a number of turns to fire a shooter marble M₃ such as shown in FIG. 1D, and each successful shot would earn a player the number of points designated at the end of the line from which the shot is made. The winning player is the one with the most points after a predetermined number of shots have been made.

The playing surface 2 can be formed on a rigid flat board or on a layer of foldable material, felt, for example, that can be placed on a flat firm surface such as a table.

Whereas a playing surface could be as shown in FIG. 1A, shooting positions P₁ through P₇ at the ends of the lines L₁ through L₇ could be shown and the lines L₁ through L₇ eliminated as shown in FIG. 2A. Indicia of the shooting positions P₁ through P₇ other than dots could be used. The shooting positions P₁ through P₅ need only be shown along one side of the playing surface along with the one of P₆ and P₇ that is nearer that side, but it is preferable to show all shooting positions in order to accommodate left and right-handed players. In FIG. 2A, the playing surface 2 is made of hard material so that depressions D₁ and D₂ for the position

of the marbles M_1 and M_2 are shown. Alternatively, in the second embodiment of the invention using disk objects, as previously indicated, D_1 and D_2 are printed positions, not depressions.

The appearance of the playing surface shown in FIG. 2B is the same as that of FIG. 2A except that aiming lines A_1 through A_7 indicating the paths that are at the center of a range of permissible angles for successful shots from the shooting positions P_1 through P_7 are shown. In FIG. 2B, the playing surface 2 is made of material such as felt, for example, so that dots d_1 and d_2 are provided to show the positions of the marbles M_1 and M_2 .

FIG. 2C is like FIG. 2A, but shows sectors S_1 through S_7 that represent the ranges of the angles for successful shots. Note, however, that the aiming lines A_6 or A_7 remain because a successful shot must follow A_6 or A_7 precisely. In FIG. 2C, the surface 2 is made of hard material having both depressions D_1 and D_2 and dots d_1 and d_2 . The sectors S_1 through S_7 are defined as follows. Taking the sector S_1 as an example, a line 4 is drawn from P_1 that passes the marble M_1 at a distance that is slightly greater than a radius of the shooter marble M_3 , and a line 6 is drawn from P_1 that intersects the line L_7 at a distance from D_2 that is the sum of the radius of the marble M_2 and the radius of the shooter marble M_3 .

Although various embodiments of the invention are shown and described herein, they are not meant to be limiting. Those of skill in the art may recognize certain modifications to these embodiments, which modifications are meant to be covered by the spirit and scope of the appended claims. For example, the playing surface 2 can be provided on a thin plastic or paper sheet that can be folded or rolled to pocket size for ultimate portability.

What is claimed is:

1. A marble game comprising:
    - a flat playing surface;
    - a shooter marble for aiming and shooting across the playing surface by a player;
    - two target marbles for stationary placement on the playing surface;
    - a pair of spaced-apart first indicia applied on said playing surface for indicating the stationary placement thereon of the two target marbles in contact with each other with their successive opposing diameters being aligned with a predetermined common horizontal plane, said first indicia lying in said common horizontal plane; and
    - second indicia applied on said playing surface for indicating a plurality of shooting positions below or above the common horizontal plane of said two target marbles, from which the player can aim and shoot the shooter marble in an attempt to move one of said two target marbles away from the other, without also moving the other.
  2. A marble game as set forth in claim 1, wherein said playing surface is on a rigid, flat board.
  3. A marble game as set forth in claim 2, wherein the indicia for indicating the stationary placement of said at least two target marbles are depressions in said board.
  4. A marble game as set forth in claim 1, wherein said playing surface is on a layer of foldable material such that the two marbles placed thereon form depressions therein.
  5. A marble game as set forth in claim 1, wherein the second indicia for indicating the plurality of shooting positions are spaced lines that are parallel to said common horizontal plane of said two target marbles.
  6. A marble game as set forth in claim 1, wherein said second indicia for indicating the plurality of shooting posi-
- 25
7. A marble game as set forth in claim 1, wherein at least one said second indicia for indicating a shooting position is located at a point along a locus line that passes through one of the pair of first indicia for indicating the placement of said two target marbles, and is perpendicular to a vertical line passing through the other one of said pair of first indicia, said vertical line being perpendicular to said common horizontal plane.
  8. A marble game as set forth in claim 7, wherein said locus line is designated on said playing surface.
  9. A marble game as set forth in claim 1, wherein said playing surface is a layer of foldable material.
  10. A disk game comprising:
    - a flat playing surface;
    - a shooter disk for aiming and shooting across the playing surface by a player;
    - two target disks for stationary placement on the playing surface;
    - a pair of first indicia applied on said playing surface for indicating the stationary placement thereon of the two target disks in contact with each other with their successive opposing diameters lying in a predetermined common horizontal plane; and
    - second indicia applied on said playing surface for indicating a plurality of shooting positions below or above said common horizontal plane, from which the player can aim and shoot the shooter disk in an attempt to move one of said two target disks away from the other without also moving the other.
  11. A disk game as set forth in claim 10, where said playing surface is on a rigid, flat board.
  12. A disk game as set forth in claim 11, wherein the first indicia for indicating the placement of said at least two target disks are depressions in said board.
  13. A disk game as set forth in claim 10, wherein said playing surface is on a layer of foldable material.
  14. A disk game as set forth in claim 10, wherein said second indicia for indicating the plurality of shooting positions are spaced lines that are parallel to said horizontal plane of said two target disks.
  15. A disk game as set forth in claim 10, wherein the second indicia for indicating the plurality of shooting positions are at points spaced along locus lines that intersect lines passing through the pair of first indicia, respectively, for indicating the placement of said two target disks, said locus lines being on one side of each of the pair of said first indicia.
  16. A disk game as set forth in claim 10, wherein at least one of said second indicia for indicating a shooting position is located at a point along a locus line that passes through one of the pair of first indicia for indicating the placement of said two target disks, and is perpendicular to a vertical line passing through the other one of said pair of first indicia, said vertical line being perpendicular to said common horizontal plane.
  17. A disk game as set forth in claim 16, wherein said locus line is designated on said playing surface.
  18. A game having movable pieces consisting of marbles, or disk objects, said game comprising:
    - means for providing a flat playing surface;
    - a pair of first indicia applied on said means for providing the playing surface for indicating the placement of two

target movable pieces to compel contact therebetween in a predetermined common horizontal plane; and second indicia applied on said means for providing the playing surface for indicating a plurality of shooting positions, below or above the common horizontal plane, of a shooter movable piece.

19. A game as set forth in claim 18, wherein said means for providing a playing surface is a rigid, flat board.

20. A game as set forth in claim 19, wherein the first indicia for indicating the placement of said two movable pieces are depressions in said board.

21. A game as set forth in claim 18, wherein said means for providing the playing surface is a layer of foldable material.

22. A game as set forth in claim 18, wherein the second indicia for indicating the plurality of shooting positions are spaced lines that are parallel to said common horizontal plane of said two movable pieces.

23. A game as set forth in claim 18, wherein said second indicia for indicating the plurality of shooting positions are at points spaced along locus lines that intersect lines passing through the pair of first indicia, respectively for indicating the placement of said two movable pieces, said locus lines being on one side of each of the said pair of first indicia.

24. A game as set forth in claim 18, wherein at least one said second indicia for indicating a shooting position is located at a point along a locus line that passes through one of the pair of first indicia for indicating the placement of said two movable pieces, and is perpendicular to a vertical line passing through the other one of said pair of first indicia, said vertical line being perpendicular to said common horizontal plane.

25. A game was set forth in claim 24, wherein said locus line is designated on said means for providing the playing surface.
